UNITED STATES PATENT OFFICE.

ARTHUR E. BEAN, OF GREENVILLE, PENNSYLVANIA, ASSIGNOR OF ONE-HALF TO
THOMAS C. BOWDEN, OF GREENVILLE, PENNSYLVANIA.

LOCOMOTIVE-TENDER COAL-GATE.

1,095,371.

Specification of Letters Patent.

Patented May 5, 1914.

Application filed January 15, 1914. Serial No. 812,226.

To all whom it may concern:

Be it known that I, ARTHUR E. BEAN, a citizen of the United States, residing at Greenville, in the county of Mercer and State of Pennsylvania, have invented certain new and useful Improvements in Locomotive-Tender Coal-Gates, of which the following is a specification.

The present invention appertains to a coal gate for locomotive tenders, and aims to provide a novel and improved structure of that nature.

It is the object of the present invention to provide a gate of the character indicated, which will eradicate the numerous disadvantages incident to the old or common types of coal gates, and which will be of such unique construction as to render it simple, convenient, practical and efficient in use, as well as providing a gate of simple, substantial, unencumbered and inexpensive construction.

Some of the objectional characteristics of common or prevailing types of coal gates employed in locomotive tenders, are itemized as follows:—the difficulty of raising or removing a "rigid" type of gate; the liability of losing a detachable gate; the difficulty with certain gates, of dragging coal within reach of the fireman's scoop; the liability of certain gates to break, in case of a wreck, collision or quick stop, due to the momentum of the coal, thus causing the coal to surge forward onto the deck of the tender and engine, to the injury of the enginemen or preventing their escape; the lack of means in some types of gates for controlling or closing the opening below the gate for the coal to feed through, whereby the coal is fed in excessive quantities onto the tender deck, due to the vibration of the tender or for other causes, and thereby either causing the coal being lost off the sides of the deck, or causing the steps and deck to be covered more or less with chunks of coal which not infrequently results in the injury of the enginemen due to slipping or misstepping; the liability, with the "pantograph" type of gate, of the enginemen's fingers being cut off between the links when raising the gate; and the difficulty of operating the doors or shut-

ters of certain gates controlling the flow of coal to the shovel space.

The present invention aims to remedy the above and other defects in present day coal gates, by the provision of an improved gate structure, which is also of advantage in other respects, as will hereinafter appear.

With the foregoing and other objects in view, which will appear as the invention is better understood, the present invention resides in the combination and arrangement of the component parts hereinafter described, it being understood, that changes in the precise embodiment illustrated, may be made, in adapting the gate to various tenders, within the scope of what is claimed, without departing from the spirit of the invention.

The invention has been illustrated in its preferred embodiment in the accompanying drawings, wherein—

Figure 1 is a front view of the body of a locomotive tender having the improved gate applied thereto. Fig. 2 is a section taken on the line 2—2 of Fig. 1. Fig. 3 is a section taken on the line 3—3 of Fig. 1, the upper doors being swung open. Figs. 4, 5 and 6 are enlarged sectional details taken on the lines 4—4, 5—5 and 6—6 of Fig. 1, respectively.

In the drawings, the numeral 1 designates an ordinary locomotive tender body, which may be taken as typical. The body embodies the forward tank portions 2 having the gateway or passage 3 therebetween, and over which the usual coal board or wall 4 is mounted; the coal board or wall 4 having an opening 5 above the gateway or passage 3, and cooperating therewith to form the door or gate opening leading to the coal bin 6. A reinforcing cleat or strip 7 is preferably riveted to the front side of the coal board 4 over the opening 5. The numeral 8 designates the usual deck or shoveling space of the tender.

In carrying out the present invention, a pair of upright angle iron cleats or posts 9 have certain of their flanges riveted or otherwise secured to the sides of the gateway or opening, or to the adjacent sides of the tank portions 2, so that their other

flanges are free and project toward each other, the cleats or posts 9 extending from the deck or floor 8 to the upper end of the gate opening along the sides or edges of the said opening.

A pair of upper sheet metal doors 10 and 11 and a pair of lower sheet metal doors 12 and 13 have their remote edges hinged to the free flanges of the posts 9 by means of 10 hinges 14 having their leaves riveted to the rear sides or backs of the said flanges and doors. The doors are arranged to swing open rearwardly or inwardly, as suggested in Fig. 3, and when the doors are closed, 15 their free edges come relatively close together. The upper and lower doors, however, are spaced apart to provide an opening therebetween of several inches in height, but not sufficiently large to permit the coal to flow freely therethrough. The upper ends of the upper doors are arranged to contact with or overlap the coal board 4 when they are closed. A pair of depending or pendant stops or stop plates 15 are riveted to the 20 back of the upper doors 10 and 11 at their lower ends, so that the free or lower ends of the stops contact with or overlap the upper end portions of the lower doors. A latch 16 is pivoted to the forward side of the upper door 11 at its free edge, and is arranged to swing into engagement with a keeper 17 secured to the forward side of the upper door 10 at its free edge, when the doors 10 and 11 are closed. The latch and 25 keeper are preferably bent from bars, the free end of the latch being bent angularly to form a handle, and the keeper having its lower end riveted or otherwise secured to the door 10 and having its upper end offset 30 to receive the latch. Eye bolts 18 are engaged to the backs of the upper doors 10 and 11 at the upper ends of the said doors, and stay chains 19 are anchored or attached to the coal board or partition 4 at the sides 35 of the gate opening and have hooks 20 at their free ends to engage the eyes 18 when the doors 10 and 11 are opened, as seen in Fig. 3, to hold the said doors open. Each of the upper doors 10 and 11 are provided 40 with a pair of adjoining openings 21 at their central portions, which are sufficiently large, to permit of the introduction of coal bars therethrough.

A latch 22, similar to the latch 16, is pivoted to the front side of the door 10 at its lower end, so that the free end of the latch 22 can be swung or engaged over the front side of the lower door 12.

A latch bar 23 of angle iron has one flange 60 pivoted at one end to the front side of the lower door 13 intermediate its edges and adjoining its upper end, and a horizontal keeper 24, similar to the keeper 17, is secured to the front side of the lower door 12 65 intermediate its edges and adjoining its

upper end, so that the keeper 24 may receive the free end of the said flange when doors 12 and 13 are closed. Keepers 25 are secured to the free edge portions of the doors 12 and 13 to receive the central or intermediate portion of the said flange, for assisting in locking the doors and bracing the same against bulging forwardly under the pressure of the coal. The other flange of the latch bar 23 projects away from the 70 doors and terminates short of the free end of the first mentioned flange, the second mentioned flange having an opening or slot 26 therein forming a hand hold.

A leaf spring or yieldable catch 27 has its 80 butt end riveted, together with a spacing block 28, to the front side of the upper door 11, so that the free end of the latch bar 23 may swing in back of the free end or tip of the spring or catch 27, the free end of the 85 spring being curved or bent, as at 29, to frictionally receive and hold the latch bar. Thus, under certain conditions, the latch bar 23 may be swung upward to engage the upper door 11 for locking the superposed 90 doors 11 and 13 together. The lower doors 12 and 13 have their lower free corners cut away, as at 30, whereby the said cut away portions coöperate to form a coal or shoveling opening leading under the gate from the 95 bin to the shoveling deck 8.

To control the coal opening 30—30, a pair of auxiliary doors or shutters 31 are pivoted, as at 32, at certain corners to the front sides of the lower doors 12 and 13 at the sides of 100 the opening and at the lower ends of the said doors. The shutter or valve doors 31 are of pentagonal contour and when the shutter doors are closed a pair of their sides 105 swing together, as at 33, it being understood that the shutter doors swing along or adjoining the faces or front sides of the main doors 12 and 13. Those sides 34 of the shutter doors 31 opposite the pivoted corners, or next above the sides 33, diverge and are 110 curved so as to engage and work within arcuate guides 35 curved about the pivots 32 as centers, and having their upper edges riveted to the faces of the doors 12 and 13, with their lower edge portions offset to receive the sides or edge portions 34 of the doors 31. The guides 35 extend from the free to the pivoted edges of the main doors 115 12 and 13, to thereby permit the shutter doors to swing open, the sides 36 of the shutter doors enabling the same to swing sufficiently over the pivots to overbalance and to clear the coal opening 30—30. The remote sides 37 of the doors 31 are arranged to strike stops 38 secured to the lower pivoted 125 corners of the doors 12 and 13 when the doors 31 are swung open, so that the doors 31 will be held open by their own weights, the doors 31 swinging over the pivots 32, in opening and closing, so as to bring the 130

centers of gravity to the respective sides of the pivots for holding the said doors either closed or open. The pivots 32 are arranged midway between the edges of the doors 12 and 13. The lower sides or edges 39 of the shutter doors 31 extending from the pivoted corners to the meeting sides 33, are spaced slightly from the deck or floor 8, as are also the lower ends of the doors 12 and 13, depending spacing or supporting strips or pieces 40 being riveted or secured to the front faces of the shutter doors 31 at their lower free corners between the sides 33 and 39, to contact with or rest upon the deck or floor 8 to support the doors 31 when closed. To brace or reinforce the shutter doors 31, angle iron members or ribs 41 are riveted to the front faces of the same at points spaced from the pivots 32, and extend from those portions between the sides or edges 33 and 39 covering the opening 30—30, to the opposite portions which overlap the main doors, so that the first mentioned portions will be braced against the pressure of the coal bearing against the backs of the doors. In order to convenience the manipulation of the shutter doors, handles 42 are secured thereto between and parallel with certain of the reinforcing members 41.

36. In use, before the tender is filled with coal, all of the doors are closed, as seen in Fig. 1, the latch or locking bar 23 being engaged to the keepers 24 and 25, the latch 16 being engaged to the keeper 17, and the latch 22 being engaged to the door 12. The latch bar 23 locks the lower doors 12 and 13 firmly together; while the latches 16 and 22 hold the upper doors 10 and 11 closed prior to the filling of the tender. The tender is then supplied with coal to fill the bin 6, the coal piling up against the doors of the gate structures. The latch bar 23 and its pivot and keepers effectively brace the lower doors 12 and 13 against bulging forwardly, while the upper ends of the upper doors in overlapping the coal board, and the stops 15 at the lower ends of the upper doors in overlapping or contacting with the lower doors, will steady the upper doors against the pressure of the coal. In this manner, the doors form a substantial barrier for holding the coal back from the deck, or for resisting the pressure of the coal, even in case of the great forward momentum of the coal in case of a quick stop or accident, such as a wreck or collision.

When the coal is to be used, the pivot or shutter doors 31 are swung open as seen in dotted lines in Fig. 1, to release the coal through the coal opening 30—30, so that the coal may be readily shoveled or scooped from the deck 8. The doors 31 stay open by their own weight, as above intimated. If a smaller supply of coal is desired, only one of the doors 31 need be opened. To shut off the flow of coal, the doors 31 may easily be swung closed partially or entirely. When the pivot or shutter doors 31 are open and the coal has been consumed from the tender to such an extent that the remaining coal no longer feeds by gravity through the coal opening 30—30, the coal can then be worked down to the said opening by inserting a suitable bar through one of the openings 21 of the upper doors 10 and 11, and also by reaching through the opening between the upper and lower doors with the bar. Then when the coal is out of reach of the poking bar and shovel or scoop, latches 16 and 22 are released, and the upper doors 10 and 11 are thus liberated and may be swung open, as seen in Fig. 3, the upper doors being held open by the stay chains 19 which have their hooks 20 engaged to the eye bolts 18 carried by the backs of the said doors. Then, the coal may be reached, by a bar or other implement, over the lower doors to drag the coal to the coal opening 30—30. When the coal cannot be reached over the lower doors, the coal having been consumed from the front end of the bin, the lower doors 12 and 13 are swung open below the opened upper doors 10 and 11, the latch bar 23 having been lifted out of engagement with the keepers 24 and 25. The latch bar 23 can then be swung upward to be engaged at its free end by the catch 27 of the upper door 11, to thus lock the lower door 13 open. The lower door 12 may be held open by engaging the latch 22 of the upper door 10 thereover. When the lower doors are thus opened, the fireman or engineman may readily enter the bin to get at the remaining coal. After the tender is emptied, the supply of coal may be replenished as above intimated, the doors all having been closed.

The advantages of the present structure are numerous. Thus, when the doors are closed, they will be effectively prevented from bulging forwardly or breaking under the pressure of the coal, even when the locomotive is stopped suddenly, as when a wreck occurs. This eliminates the danger of the coal surging forward onto the decks of the tender and engine, which is objectionable for obvious reasons. The pivoted doors 31 can be so operated, as to limit to a nicety, the supply of coal onto the tender deck, whereby the supply of coal will not be excessive, but will be limited to the amount needed for firing the engine. When firing is not being done, as for instance, in drifting, the supply of coal may be entirely shut off by closing the pivoted doors 31. In this manner, by restricting the supply of coal onto the tender deck to actual needs, there is no stray or excessive coal on the deck, which might fall off the sides of the decks of the tender and engine, or which

130

might be accidentally tréad on to cause injuries. The present device enables the gangway and steps to be kept clear of coal, thus providing safety for life and limb. 5 There is no danger, when opening the present gate, of the fireman getting his fingers caught, crushed or cut off, as sometimes happens with the pantograph type of gate.

10 The present device is economical in application and maintenance, and can be applied to old as well as new tenders.

15 The coal or shoveling opening may be readily closed, due to the fact that the shutter doors are pivoted and have relatively sharp edges, the doors 31 being constructed of sheet metal, so that the lower edges of the doors have a shearing or cutting action against the coal, thereby enabling the said doors to cut through the 20 coal with comparative ease. The construction of the doors 31 is also of considerable moment, for the several reasons hereinbefore mentioned, it being further noted that the reinforcing members or ribs 41 being 25 disposed approximately parallel with the sides or edges of the said doors opposite the pivoted corners, or which engage the guides, will brace the lower corner portions of the said doors against bending forwardly under the pressure of the coal, when 30 the said doors are closed, inasmuch as the reinforcing ribs or means extend from the said lower portions, which cover the coal opening, to the opposite portions, which 35 overlap the lower hinged doors. The doors 31 engaging the guides will also assist in holding the doors 31 against the faces of the lower hinged doors.

40 Especial attention is directed to the fact that the remote ends of the cut-away portions 30 terminate approximately midway between the upright edges of the lower doors 12 and 13, and that the supplemental doors 31 are pivoted to the said lower doors 45 adjacent the said ends of the cut-away portions 30 and the lower ends of the said lower doors, whereby the pivoted doors 31 may swing open and closed in the peculiar manner above described. Thus, the pivoted 50 doors 31 are held open and closed by their own weights, and are peculiarly adapted for opening and closing the shovel opening.

55 The present device also permits ready access to the tender draw bar pin, for the reason that by closing the coal opening as above indicated, the coal can be held back from the deck, which, if it occurred, as under present day conditions, would necessitate considerable shoveling to uncover the 60 draw bar pin.

65 The present gate has a practically smooth back against which the coal rests, whereby the coal may readily gravitate to the coal or shoveling opening. It is not necessary, as usual, to pound or jar the doors or gate, to

loosen the coal from the back of the same, inasmuch as there are no projections on the back thereof upon which the coal can lodge. The present gate does not require raising or removal, as do the present "rigid" or sliding gates, to get at the coal, the present doors being readily swung open. The several parts of the present device cannot become accidentally detached and lost, as all parts are connected directly or indirectly to 70 the tender. The present gate enables the coal to be easily brought within reach of the shoveler or fireman, and the supply of coal through the gate may easily be controlled, as needed. There is no space between the gate and the coal board, thus preventing the coal from falling over the top of the gate.

75 The present coal gate not having the above mentioned and other objectionable features, which exist in present gates, and being of advantages for the reasons above mentioned, and for other obvious reasons, fulfils the 80 purposes of its design, including safety to life and limb, convenience, durability, economy of application and maintenance, and prevention of loss of fuel.

85 Having thus described the invention, what is claimed as new is:—

90 1. A locomotive tender coal gate embodying a pair of hinged doors having their 95 lower free corners cut away to provide a coal opening, and the remote ends of the cut-away portions terminating approximately midway between the upright edges 100 of the said doors, a pair of supplemental doors pivoted to the aforesaid doors adjacent the said ends of the cut-away portions and the lower ends of the said doors and arranged to swing over their pivots to and 105 from the said opening to be held in closed or open positions by their weights.

110 2. A locomotive tender coal gate embodying a pair of hinged doors having their lower free corners cut away to provide a 115 coal opening, and a pair of sheet metal supplemental doors pivoted to the aforesaid doors and arranged to have certain portions thereof swing together over the said opening with the other portions overlapping the hinged doors, the pivoted doors having reinforcing means at spaced points, from the pivots and extending from the first mentioned to the second mentioned portions.

120 3. A locomotive tender coal gate embodying a pair of hinged doors having their lower free corners cut away to provide a coal opening, and a pair of sheet metal supplemental doors pivoted to the aforesaid doors at the opposite sides of the said opening, the pivoted doors being arranged to swing over their pivots to and from the said opening to be held in closed and open positions by their weights, and being arranged 125 to have certain portions thereof swing to- 130

gether over the said opening with the other portions overlapping the hinged doors, the pivoted doors having reinforcing means at spaced points from the pivots and extending from the first mentioned to the second mentioned portions.

4. A locomotive tender coal gate embodying a pair of hinged doors having their lower free corners cut away to provide a 10 coal opening, a pair of supplemental doors pivoted to the aforesaid doors at the opposite sides of the said opening and arranged to swing over their pivots to and from the said opening to be held in closed or open positions by their weights, and stops carried by the hinged doors and arranged to be engaged by the pivoted doors when they are opened to thereby support the same.

5. A locomotive tender coal gate embodying a pair of hinged doors having their lower free corners cut away to provide a coal opening, a pair of sheet metal supplemental doors pivoted to the aforesaid doors at the opposite sides of the said opening, the 20 pivoted doors being arranged to swing over their pivots to and from the said opening to be held in closed and open positions by their weights, and being arranged to have certain portions thereof swing together over the 25 said opening with the other portions overlapping the hinged doors, the pivoted doors having reinforcing means at spaced points from the pivots and extending from the first mentioned to the second mentioned portions, 30 and stops carried by the hinged doors and arranged to be engaged by the pivoted doors when they are opened to thereby support the same.

6. A locomotive tender coal gate embodying a pair of hinged doors having their lower free corners cut away to provide a coal opening, a pair of supplemental doors pivoted to the aforesaid doors and arranged to swing together over the said opening, and 40 arcuate guides, curved about the pivots of the pivoted doors as centers, carried by the hinged doors and receiving those portions of the pivoted doors opposite the pivoted portions.

50 7. A locomotive tender coal gate embodying a pair of hinged doors having their lower free corners cut away to provide a coal opening, a pair of supplemental doors pivoted to the aforesaid doors at the opposite 55 sides of the said opening and arranged to swing over their pivots to and from the said opening to be held in closed or open positions by their weights, and arcuate guides, curved about the pivots of the pivoted doors as centers, carried by the hinged doors and receiving those portions of the pivoted doors opposite the pivoted portions.

8. A locomotive tender coal gate embodying a pair of hinged doors having their 60 lower free corners cut away to provide a

coal opening, a pair of sheet metal supplemental doors pivoted to the aforesaid doors and arranged to have certain portions thereof swing together over the said opening with the other portions overlapping the hinged 70 doors, the pivoted doors having reinforcing means at spaced points from the pivots and extending from the first mentioned to the second mentioned portions, and arcuate guides, curved about the pivots of the pivoted doors as centers, carried by the hinged doors and receiving those portions of the pivoted doors opposite the pivoted portions.

9. A locomotive tender coal gate embodying a pair of hinged doors having their lower free corners cut away to provide a 80 coal opening, a pair of sheet metal supplemental doors pivoted to the aforesaid doors at the opposite sides of the said opening, the pivoted doors being arranged to swing over the pivots to and from the said opening to be held in closed and open positions by their weights, and being arranged to have certain portions thereof swing together over the said opening with the other portions overlapping the hinged doors, the pivoted doors having reinforcing means at spaced points from the pivots and extending from the first mentioned to the second mentioned portions, and arcuate guides, curved about the pivots 90 of the pivoted doors as centers, carried by the hinged doors and receiving those portions of the pivoted doors opposite the pivoted portions.

10. A locomotive tender coal gate embodying a pair of hinged doors having their lower free corners cut away to provide a coal opening, a pair of supplemental doors pivoted to the aforesaid doors at the opposite sides of the said opening and arranged to swing over their pivots to and from the said opening to be held in closed or open positions by their weights, stops carried by the hinged doors and arranged to be engaged by the pivoted doors when they 100 are opened to thereby support the same, and arcuate guides, curved about the pivots of the pivoted doors as centers, carried by the hinged doors and receiving those portions of the pivoted doors opposite the pivoted portions.

11. A locomotive tender coal gate embodying a pair of hinged doors having their lower free corners cut away to provide a coal opening, a pair of sheet metal supplemental doors pivoted to the aforesaid doors at the opposite sides of the said opening, the pivoted doors being arranged to swing over their pivots to and from the said opening to be held in closed and open positions by their 120 weights, and being arranged to have certain portions thereof swing together over the said opening with the other portions overlapping the hinged doors, the pivotal doors having reinforcing means at spaced points from the 125

130

5 pivots and extending from the first mentioned to the second mentioned portions, stops carried by the hinged doors and arranged to be engaged by the pivoted doors when they are opened to thereby support the same, and arcuate guides, curved about the pivots of the pivoted doors as centers, carried by the hinged doors and receiving those portions of the pivoted doors opposite the pivoted portions.

10 12. A locomotive tender coal gate embodying a pair of hinged doors having their lower free corners cut away to provide a coal opening, a pair of supplemental pentagonal doors each having one of their corner portions pivoted to one of the hinged doors at the side of the said opening and at the lower end of the said hinged door, arcuate guides, curved about the pivots of the pivoted doors as centers, carried by the hinged doors and receiving those sides of the pivoted doors opposite the pivoted corner portions, the guides extending from the free to the pivoted edges of the hinged doors, and stops carried by the hinged doors at their lower pivoted corners for the engagement of the remote sides of the pivoted doors adjacent the pivoted corner portions, when the pivoted doors are opened.

15 13. A locomotive tender coal gate embodying a pair of hinged doors having their lower free corners cut away to provide a coal opening, a pair of supplemental sheet metal pentagonal doors each having one of their corner portions pivoted to one of the hinged doors at the side of the said opening and at the lower end of the said hinged door, arcuate guides, curved about the pivots of the pivoted doors as centers, carried by the hinged doors and receiving those sides of the pivoted doors opposite the pivoted corner portions, the guides extending from the free to the pivoted edges of the hinged doors, and stops carried by the hinged doors at their lower pivoted corners for the engagement of the remote sides of the pivoted doors adjacent the pivoted corner portions, when the pivoted doors are opened, the pivoted doors having reinforcing means at spaced points from the pivots and arranged approximately parallel to those sides received by the guides.

20 14. The combination with a locomotive tender having a gate-way, of doors hinged to the sides of the gate way and having their lower ends spaced above the deck of the

tender, the lower free corners being cut away to provide a coal opening, supplemental doors pivoted to the hinged doors at the sides of the said opening to swing to and from the said opening, and depending spacing members carried by the pivoted doors to engage the deck when the pivoted doors are closed.

25 15. The combination with a locomotive tender having a gate way, of a pair of lower and a pair of upper doors hinged to the sides of the gate way, the lower free corners of the lower doors being cut away to provide a coal opening, the adjacent ends of the doors being spaced apart and the upper doors having openings therein.

30 16. The combination with a locomotive tender having a gate way and a coal board over the gate way, of a pair of lower and a pair of upper doors hinged to the sides of the gate way, the lower doors having their lower free corners cut away to provide a coal opening; and means carried by the lower doors for bracing the same against bulging forwardly when closed, the upper doors having portions at their upper and lower ends to overlap the backs of the coal board and lower doors, respectively when the upper doors are closed.

35 17. The combination with a locomotive tender having a gate way and a coal board over the gate way, of a pair of upper and a pair of lower doors hinged to the sides of the gate way to swing open rearwardly, the lower doors having their lower free corners cut away to provide a coal opening, a latch bar pivoted to one of the lower doors, a keeper carried by the other lower door for receiving the latch bar, the upper doors having portions at their upper and lower ends to overlap the backs of the coal board and lower doors, respectively, when the upper doors are closed, coöoperating means carried by the upper doors and tender for holding the upper doors open, a catch carried by one upper door for engaging the free end of the latch bar when swung upward, means carried by the upper doors for locking them closed, and means for locking the other upper door and that lower door, having the keeper, together.

40 In testimony whereof I hereby affix my signature in presence of two witnesses.
